UNITED STATES PATENT OFFICE.

SAMUEL L. HANSON, OF ALBERT LEA, MINNESOTA.

HAY SLING.

Application filed May 31, 1928. Serial No. 281,915.

This invention relates to a hay sling and more especially to a novel form of eye for attachment to the free end of each hook, one of the objects being to eliminate rings, clamps, 5 and other devices heretofore used and to leave a light, smooth end free of objectionable protuberances and will not catch in the hay.

A further object is to provide a terminal member or eye of this type which can be applied without requiring the services of a skilled mechanic and, when once placed in position, will be held securely to the rope.

With the foregoing and other objects in view which will appear as the description 15 proceeds the invention resides in the combination and arrangement of parts and in the details of construction hereinafter described and claimed, it being understood that changes in the precise embodiment of the invention 20 herein disclosed may be made within the scope of what is claimed without departing from the spirit of the invention.

In the accompanying drawings the preferred form of the invention has been shown.

25 In said drawings,

Figure 1 is an elevation of a hay sling embodying the present improvement, portions of the rope being broken away.

Figure 2 is a plan view of one of the 30 terminal or eye members.

Figure 3 is a side elevation thereof.

Figure 4 is a section on line 4—4, Figure 2.

Figure 5 is a plan view of the terminal or eye member showing the relative positions 35 of the sides thereof when the member is compressed on the rope to which it is applied.

Figure 6 is a view similar to Figure 2 showing a slightly modified form of terminal member.

40 Referring to the figures by characters of reference 1 designates a casting from which the ropes 2 are extended. In the structure illustrated one rope is threaded through apertures 3 in the side portions of the casting 45 and extended transversely between these apertures. Another rope 4 is secured within an intermediate opening 5 in the casting. The means for attaching the ropes to the casting 50 does not constitute any part of the present invention.

Located at the free end of each rope is an eye member indicated generally at 6 which can be formed of a malleable casting and is provided in one end portion with an eye 7 while its other end portion is in the form of 60 an elongated loop 8. An intermediate open-

ing 9 may be provided between the loop 8 and the eye 7.

Extending inwardly from the side portions of the loop 8 adjacent the center thereof are 60 projections 10 each of which is cut away to form a shoulder 11. The shoulders are so positioned that, when the sides of the loop are thrust toward each other, the shoulders 11 will be brought into lapped relation as shown 65 in Figure 5.

Before the eye member is applied to the end portion of a rope the same is shaped substantially as shown in Figure 2. The end portion of the rope is braided through the eye 7 70 and opening 9 and also through that portion of the loop 8 between the opening 9 and the inwardly projecting portions 10. After the strands of the rope have been drawn tightly 75 the sides of the loop 8 are forced toward each other by means of a hammer or any other suitable tool, thereby pinching that portion of the rope within the loop and causing the shoulders 11 to lap as shown in Figure 5.

Consequently the member will be held securely to the rope and that portion of the loop 8 extending beyond the end of the rope can be used in fastening the rope about a load. The ends of the rope can of course be trimmed 80 off so that there will be no objectionable projecting portions. It has been found in practice that when a rope is connected to a member as described, the parts will not become separated and the structure is advantageous because it leaves a light and smoothly finished 85 end.

A modification of this device has been illustrated in Figure 6 wherein, instead of providing the elongated closed loop 9, a shank 12 can be interposed between the end eye 13 and the loop 14 with its inwardly extended intermediate projections 15. This terminal member can be used just as efficiently as the one previously described, particularly if a ring, indicated in section at 16 in Figure 6 is 90 clamped about that portion of the braided rope extending along the shank 12.

What is claimed is:

1. In a hay sling a one piece member having an eye in one end, an intermediate opening, and an elongated loop at its other end, a rope having one end braided within the eye and the intermediate opening and within one end portion of the loop, the sides of the loop being clamped upon the end of the braided portion of the rope.

2. The combination with a rope of a hay

sling, of an elongated member having its eye in one end, the elongated loop at its other end, and an intermediate opening, one end of the rope being braided through the eye and opening and into one end portion of the loop, the side portions of the loop being compressed upon the braided portion of the rope in said loop, and inwardly extending lapping portions at the sides of the loop.

5 10 3. A member for attachment to the end of a rope, including an eye at one end, an elongated loop at its other end, an intermediate opening, and inwardly extending projections at the sides of the loop adjacent the centers thereof adapted to lap when the loop is contracted transversely.

4. A member having an eye in one end, an elongated loop at its other end, and an intermediate opening, a rope having one end portion braided within the eye and in one end portion of the loop, and inwardly projecting portions at the sides of the loop adapted to lap, when the loop is contracted transversely, thereby to enclose a portion of the rope in 20 one end portion of the loop.

5. In a hay sling a one-piece member having an eye in one end and an elongated loop in its other end, a rope having one end braided within the eye and a portion of the loop, the 30 sides of the loop being clamped upon the ends of the braided portion of the rope and a portion of the loop being extended beyond the end of the rope, said rope terminating in the loop.

35 6. The combination with a rope of a hay sling, of an elongated member having an eye

in one end and an elongated loop at its other end, one end of the rope being braided through the eye and loop, the side portions of the loop being compressed upon the braided portion of the rope in the loop, and inwardly extending lapping portions at the sides of the loop.

7. A member for attachment to the end of a rope, including an eye at one end, an elongated loop at the other end, and inwardly extending projections at the sides of the loop adjacent the centers thereof adapted to lap when the loop is contracted transversely.

8. A member having an eye in one end, an elongated loop at its other end, a rope having one end portion braided within the eye and in one end portion of the loop, and inwardly projecting portions at the sides of the loop adapted to lap when the loop is contracted transversely, thereby to enclose a portion of the rope in one end portion of the rope and bind upon it.

9. A member having an eye in one end, an elongated loop at its other end, a rope having one end portion braided within the eye and in one end portion of the loop, inwardly projecting portions at the sides of the loop adapted to lap when the loop is contracted transversely, thereby to enclose a portion of the rope in one end portion of the rope and bind upon it, and means for binding upon that portion of the rope between the eye and the loop.

In testimony that I claim the foregoing as 70 my own, I have hereto affixed my signature.

SAMUEL L. HANSON.
